UNITED STATES PATENT OFFICE.

RALPH B. COOLEY, OF BROOKLYN, NEW YORK.

DESIGN FOR A TEN-PIN.

SPECIFICATION forming part of Design No. 16,068, dated May 5, 1885.

Application filed April 9, 1885. Term of patent 7 years.

To all whom it may concern:

Be it known that I, RALPH B. COOLEY, a resident of Brooklyn, in the county of Kings and State of New York, have invented and 5 produced, by my own industry, genius, efforts, and expense, a new and original Design for a Ten-Pin, of which the following is a full description, in connection with the accompanying photograph, which represents a side view 10 of my new ten-pin.

This invention relates to the new configuration of a ten-pin. The same consists of a base, A, having flat top and rounded sides, on which base stands a tapering leg-shaped support, B, for the body C, which body is of substantially cylindrical form, with tapering upper end, a, which connects by the neck b with the cylindrical head or top D, that has the projecting brim d.

I claim—

The design for a ten-pin, the same consisting of the parts A, B, C, D, b, and d, substantially as shown.

RALPH B. COOLEY.
